UNITED STATES PATENT OFFICE.

FRANK H. SCHWERIN, OF BELLEVUE BOROUGH, PENNSYLVANIA, ASSIGNOR TO THE DUFF MANUFACTURING COMPANY, OF PITTSBURGH, PENNSYLVANIA, A CORPORATION OF PENNSYLVANIA.

TIE SPACER.

Application filed October 8, 1926. Serial No. 140,233.

This invention relates to that class of devices known as tie spacers, the same being tools applicable to a railroad rail to coact with a jack acting between the device and a tie, for the purpose of shifting the tie in the roadbed, the thrust of the jack causing the tie spacer to engage the rail with a fixed grip so that the tie spacer affords a solid abutment for the jack.

The object of the invention, generally stated, is to provide a tool of this character which cooperates with the jack and enables the jack to be applied to the tie and tie spacer, in the most advantageous manner, and this irrespective of the angle at which the tie spacer may set on the rail, which will engage rails of different sizes with equal facility and firmness, and which is applicable in either a right or left-hand position.

In the accompanying drawings, forming part hereof:

Fig. 1 is a plan view of the tie spacer applied to a rail, with a jack in operative position between the spacer and a tie;

Fig. 2 is a vertical sectional view taken through the head of the tie spacer and parallel with the rail, the parts being in elevation; and

Fig. 3 is an elevation of the tie spacer.

The tie spacer comprises a yoke 2, formed to extend across beneath the base and base flanges of a rail *a*, with jaws 3, 4, for gripping the flanges at opposite sides. The grip is obtained by horizontal skewing of the spacer on the rail, the pressure of the jack *b* exerted against a head 5 formed integral with one end of the yoke forcing the device into firmer engagement with the rail the

greater the pressure. The gripping action is obtained most advantageously, particularly on rails of different sizes or sizes of base, by so constructing the yoke as to seize the flanges between the overhanging jaws

bearing on top of the flanges and the under-rail part of the yoke bearing on the bottom face of the rail, the tendency of the jaws to ride up the top slopes of the flange when the spacer is skewed resulting in a powerful wedging grip; however, the specific gripping action may be varied. The yoke is made with such distance and clearance between the jaws that the yoke can be readily hooked onto the largest rail-base within

the range of the device, the device being 55 then skewed to an inclined position for holding as shown in the drawing. The inclination or angle between the longitudinal axis of the device and the perpendicular to the axis of the rail is greater the smaller 60 the rail base, but the device is adapted to coact in the same effective manner with the jack irrespective of such variation of angle.

The head 5 is cast integral with the yoke, 65 projecting horizontally outward beyond the jaw 4, and rising upwardly above the top plane of the ties to cooperate with the jack.

The head is formed on opposite sides with abutment faces 6 to coact with the top *c* 70 of the jack. The said faces are inclined to the longitudinal axis of the tie spacer in such relation, and are disposed at such distance outward beyond the jaw 4 and the end of the yoke proper, as to receive and sustain the thrust of the jack top when the

jack is placed parallel with the rail with its base *d* planted flat against the tie *e* to be shifted. By curving the abutment faces in the horizontal plane as shown, an effective abutment bearing is assured at the various angles which the tie spacer may assume on different rails. A wall comprising transverse ribs or flanges 7 at the inner ends of the abutment faces afford side abutments 75 for the jack top, keeping the latter from sliding in toward the rail and tilting the jack from its most advantageous position.

At the bottoms of the abutment faces ledges 8 are cast on which to rest the jack top, these ledges likewise acting to oppose overturning tendency in the spacer under the pressure of the jack applied to the upstanding head. The upper portions of the faces 6 are extended higher than the width of the top of an ordinary jack and are preferably 80 curved or inclined in the vertical plane so as to overhang the jack top somewhat, so as to prevent any possibility of the jack riding over the head of the tie spacer under the powerful pressure which is applied. 85

Naturally the specific form of the abutment faces or pockets designed to receive the thrust of the jack top may be varied, the construction shown, however, being especially effective.

The divergent walls 9 of the head 5 forming the abutment faces are connected by a horizontal internal web 10 lying directly be-

tween the abutment faces, this web contributing an important element of strength and being formed with an opening 11 affording a convenient hand-hold for carrying. The 5 yoke is made narrow at the end which carries the jaw 3 and increases in width to and through the broad, double-faced head. The ledges 8 are advantageously formed in continuation with the under-rail bar of the 10 yoke 2. The precise details, however, may be varied.

The construction of the tie spacer is such that one and the same appliance can be used on rails of different sizes, and in either right 15 or left hand position, with equal advantage as herein explained.

I claim:

1. A tie-spacer comprising a yoke constructed to extend across under and to grip 20 the base flanges of a rail by skewing horizontally thereon, and having at one end a symmetrical upstanding head, said head having on opposite sides supporting ledges and curved pockets adapted to retain a jack head 25 at the various angles which the spacer may assume on rails of different sizes.

2. A tie-spacer comprising a yoke constructed to extend across under and to grip the base flanges of a rail by skewing horizontally 30 thereon, and having at one end a symmetrical upstanding head comprising two deep divergent wing walls forming jack abutment faces at opposite sides, and an internal web connecting said walls, said web 35 being formed with an internal opening providing a handhold.

3. A tie-spacer comprising a member constructed to extend across under the base of a rail and formed at one end with a head, designed 40 to cooperate with a jack, said member

having means for engaging the flanges of the rail, said means being so designed as to wedge firmly on top and bottom of the flanges of rails of different sizes by virtue of skewing in the horizontal sense, thereby gripping 45 the rail and keeping the member substantially upright under the action of the jack.

4. A tie-spacer comprising a member constructed to extend across under the base of a rail and formed at one end with a head having faces on both sides in divergent relation designed to cooperate with a jack, said member having means for engaging the flanges of the rail, said means being so designed as to wedge firmly on top and bottom of the flanges of rails of different sizes by virtue of skewing in the horizontal sense, thereby gripping 50 the rail and keeping the member substantially upright under the action of the jack.

5. A tie-spacer comprising a member constructed to extend across under and to grip the base of a rail by virtue of skewing horizontally thereon, said member having at one end an upstanding head provided with divergent wing walls each forming a jack seat 60 upwardly curving to overhang the head of the jack.

6. A tie-spacer comprising a member having a portion which extends across under the rail and is provided with means including a jaw for engaging the rail flanges, a transverse wall rising from said portion adjacent said jaw, deep divergent wing walls extending outward from said transverse wall forming two jack abutment faces, and an internal wall joining said wing walls.
